TWO-STAGE FUEL UNIT

William Ray Kiefer, Rockford, Ill., assignor to
 Sundstrand Machine Tool Co., a corporation of
 Illinois

Application February 16, 1951, Serial No. 211,244

8 Claims. (Cl. 103—6)

1
 This invention relates to a pump and more particularly to a two-stage oil burner pump unit in which a first stage pump is effective to draw oil into and from a reservoir in the casing of the unit and from which it is supplied by gravity to a second stage pump.

It is the general object of the invention to provide a new and improved two-stage oil burner pump unit.

Another object is to provide a two-stage pump unit embodying a reservoir, a second stage pump having its inlet connected to a lower portion of said reservoir, and a first stage pump with its inlet connected to the upper portion of the reservoir and its outlet connected back to the supply tank.

A further object of the invention is to provide a pump of the type described in the preceding paragraphs so arranged that the first stage pump discharges into the supply tank while the excess from the second stage pump is returned to the reservoir in order to minimize the circulating oil supply for both pumps.

Another object of the invention is to provide a two stage pump unit in which the inlets of both pumps are connected in parallel so that the first stage pump operates to assist the second stage pump to pull oil into the pump reservoir.

Another object of the invention is to produce a two stage pump in which the inlet for the first stage is located near the top of the reservoir and the inlet for the second stage is located near the bottom of the reservoir and in which the first stage sucks oil into the reservoir while simultaneously removing air and excess oil therefrom whereby the second stage pumps only oil free of entrained air and vapor.

Other objects will become readily apparent from the following detailed description taken in connection with the accompanying drawings, in which:

Fig. 1 is a longitudinal central section through a preferred form of the invention;

Fig. 2 is a section approximately along the line 2—2 of Fig. 1;

Fig. 3 is a diagrammatic view of the fuel circuit, and

Fig. 4 is a view like Fig. 3 of a modified form of circuit.

While there is shown in the drawings and herein described in detail two embodiments of the invention, it is to be understood that the invention is not limited to the specific forms disclosed but includes all modifications and alternative constructions falling within the spirit and scope of the appended claims.

2
 In the forms chosen for purposes of disclosure, the invention comprises generally a two-part casing 10, 11, a first pumping device or means 12, a second pumping device or means 13, a drive shaft 14, a mechanical seal 15 for the drive shaft, a strainer 16, and a control valve mechanism 17. It is contemplated that the shaft 14 will be connected by suitable means to a driving motor (not shown), that an inlet port 18 will be connected to a source of fluid supply, and a discharge port 19 to a burner nozzle. The casing parts are formed to provide a substantially cylindrical chamber or recess 20, in which the pumping devices 12 and 13 and strainer 16 are positioned 15 for purposes hereinafter more fully described.

As illustrated herein, the casing part 10 is in the form of a body member which is also used for supporting the fuel unit. Preferably, this member is formed with supporting lugs 21 having bolt receiving apertures 22 (Fig. 2). The part 11 is in the form of a closure or cover and is bolted to the part 10 by means of a plurality of screw devices 23.

The pumping devices 12 and 13 comprise end plates 24 and 25, an intermediate plate 26 and annular spacing members 27 and 28. A first stage pump comprising a roller or pinion 29 and an intermeshing toothed ring 30 are operable in the chamber formed intermediate the plates 24 and 26, and a second stage pump comprising a roller or pinion 31 and a toothed ring 32 operate in the chamber formed intermediate the plates 26 and 25. The rollers 29 and 31 are provided with driving pins 33 and 34 respectively which interengage with a key-way 35 in the drive shaft 14 when the pumping unit is assembled.

A crescent 36 for the first stage pump is suitably secured to the plate 24, and a crescent 37 is secured to the end plate 26 for the second stage pump.

The end plate 24 contains an inlet port 40 which extends through the periphery of the plate 24 for supplying fluid to the first stage pump. The intermediate plate 26 has an arcuate discharge cavity 42 which is connected with channel port 43 formed in the plates 26, 28 and 25. Oil in the channel port 43 is directed into a passage 44 which extends downwardly in the member 10 into an annular recess 45 which is joined to a return port 46. The second stage pump is provided with fluid from the bottom of the chamber 20 through an inlet port 50 formed in the plate 26. Fluid discharged from the second stage passes through an outlet port 51 (Fig. 3) which communicates with a valve chamber 52.

55 In the form of the invention illustrated here-

3

in, the casing part 10 has an appendage portion 60 provided with a transversely extending bore 61. The valve chamber 52 is formed in this bore between the adjacent end of an end cap 62, which is screw-threaded into one end of the bore, and a sleeve member 63 which is inserted into the central portion of the bore. The end cap 62 contains a discharge port 64. A hollow piston valve 65 is slidably mounted in the sleeve 63 so that the operative end 66 thereof will be subjected to the fluid in the valve chamber 52. This valve is held seated to close the discharge port 64 by means of a coiled spring 67 which is positioned within the hollow piston valve. A cap member 68 screw-threaded in the other end 15 of the bore 61 carries a screw device 69, the free end of which engages in a cup-shaped member 70 seated against the adjacent end of the spring 67 to provide for adjusting the pressure of the spring on the piston valve and thereby the fluid pressure at which the valve opens. Preferably, a removable closure 71 is threaded on the cap 68 to seal the return pressure which may cause leakage past the screw threads as well as to protect the adjusting screw device 69 and facilitate access thereto to permit inserting a screw driver 20 to turn the screw device.

In order to by-pass excess fluid, the piston valve 65 is also arranged to uncover a by-pass port 72 which is formed in the sleeve 63 and communicates with the annular recess 45 formed around the sleeve 63. The sleeve 63 is provided with a longitudinal slot 73 opening at one end into the valve chamber 52. Communication between the valve chamber and the by-pass port 72 is established when the piston 65 is moved against the spring to bring an annular groove 74 in the exterior side wall of the piston into a position communicating with both the slot 73 and the port 72. The annular passage 45 communicates with the return or by-pass port 46 which is closed by a plug 75 at its upper end (Fig. 1), and communicates at its lower end with the exterior of the casing to provide an external by-pass which may be connected to a pipe 76 leading back to the supply tank.

When in use, a pump as illustrated herein may (as shown in Fig. 3) have its inlet port 18 connected to a supply tank 78 by means of a pipe 77 so that fuel oil may be drawn from the supply tank through the pipe 77 and inlet port 18 into the chamber 20. With the pumping device in operation, the first stage pump and second stage pump, through their inlet ports 40 and 59, exhaust the chamber 20 until oil from the tank fills the chamber to the oil level as indicated in Fig. 3, thereafter both pumps continue to draw oil from the supply tank into the chamber 20 with the first stage withdrawing excess oil and entrained air from above the oil level and the second stage pump by virtue of its port location drawing only liquid fuel free of entrained air and vapor. The excess oil and air are returned through the port 43, passage 44, recess 45, port 46 and return pipe 76 to the supply tank 78. With the chamber 20 supplied with oil, the second stage pump receives oil under gravity therefrom through the inlet port 50 and discharges it under pressure to the outlet port 51 which leads to the control valve chamber 52.

A somewhat modified form of circuit is shown in Fig. 4. Many of the features of this circuit are similar to those shown in Fig. 3 and where such similarity exists similar reference numerals have been employed.

4

The circuit of Fig. 4 is so arranged that the first stage pump has its inlet 40 bisected by the normal oil level within the reservoir. Inasmuch as a considerable portion of the entrained air accumulates near the surface of the oil in the reservoir a more effective withdrawal of air from the oil can be accomplished by so arranging the inlet 40 with respect to the normal oil level. The discharge port from the first stage pump is connected directly to the tank rather than being added to the excess oil from the second stage pump as in the previous embodiment. The second stage pump is provided with an inlet 50 located at the bottom of the reservoir as previously described and discharges into the valve chamber 22. Excess oil pumped by the second stage is returned by means of the port 45 and a conduit 89 to the reservoir. Inasmuch as the oil pumped by the second stage is substantially free of entrained air and vapor, it may be returned to the reservoir without fear of contaminating the oil therein. By so arranging the disposition of excess oil pumped by the second stage the amount of oil circulated through the tank is minimized. Thus the total amount of oil circulated by the system is reduced. Like the previously described circuit, the circuit shown in Fig. 4 is one in which both pumps are effective in drawing oil into the reservoir inasmuch as they operate in parallel for this purpose.

When the circuit of Fig. 4 is employed, the discharge port 46 is closed by a plug 81 as shown.

I claim:

1. A two-stage oil burner pump having, in combination, a first stage pumping means, a second stage pumping means, a reservoir to which the inlet to the second stage pumping means is connected below the level at which the oil stands during normal operating conditions, a supply tank connection leading to said reservoir above the normal operating level of the oil therein, an inlet connection for the first stage pumping means communicating with said reservoir at the normal oil level to enable the first stage pumping means to withdraw excess oil and any air above said level, and a discharge connection from the first stage pumping means for returning excess oil and air to the supply tank.

2. A two-stage oil burner pump having, in combination, a first stage pumping means, a second stage pumping means, a reservoir to which the inlet to the second stage pumping means is connected below the level at which the oil stands during normal operating conditions, a supply tank connection leading to said reservoir above the normal operating level of the oil, an inlet connection for the first stage pumping means communicating with said reservoir at the normal oil level to enable both pumping means to suck oil from the supply tank to the reservoir and to enable the first stage pumping means to withdraw excess oil and any air above said level, and a discharge connection from the first stage pumping means for returning excess oil to the supply tank.

65 3. A two-stage oil burner pump having, in combination, a first stage pumping means, a second stage pumping means, a reservoir to which the inlet to the second stage pumping means is connected below the level at which the oil stands
70 during normal operating conditions, a supply tank connection leading to said reservoir above the normal operating level of the oil therein, an inlet connection for the first stage pumping
75 means communicating with said reservoir at the

normal oil level to enable the first stage pumping means to withdraw excess oil and any air above said level, a discharge connection from the first stage pumping means, a discharge connection for excess oil pumped by the second stage pumping means and connected to said discharge from the first stage pumping means, and means connecting the discharge from the second stage pumping means to the supply tank.

4. A two-stage oil burner pump having, in combination, a first stage pumping means, a second stage pumping means, a reservoir to which the inlet to the second stage pumping means is connected below the level at which the oil stands during normal operating conditions, a supply tank connection leading to said reservoir, an inlet connection for the first stage pumping means communicating with said reservoir to enable the first stage pumping means to withdraw excess oil therefrom, and a discharge connection from the first stage pumping means for returning excess oil to the supply tank.

5. A two-stage oil burner pump having, in combination, a first stage pumping means, a second stage pumping means, a reservoir to which the inlet to the second stage pumping means is connected below the level at which the oil stands during normal operating conditions, a supply tank connection leading to said reservoir above the normal operating level of the oil therein, an inlet connection for the first stage pumping means communicating with said reservoir at the normal oil level to enable the first stage pumping means to withdraw excess oil and any air above said level, a discharge connection from the first stage pumping means for returning excess oil and air to the supply tank, and a discharge connection from the second stage pumping means for returning excess oil pumped thereby to the reservoir.

6. A two-stage oil burner pump having, in combination, a first stage pumping means, a second stage pumping means, a reservoir to which the inlet to the second stage pumping means is connected below the level at which the oil stands during normal operating conditions, a supply tank connection leading to said reservoir above the normal operating level of the oil therein, an inlet passage connected to the first stage pumping means and opening to said reservoir, the opening of said passage being bisected by the oil at normal level in the reservoir to enable the first stage pumping means to withdraw excess

oil and any air above said level, and a discharge connection from the first stage pumping means for returning excess oil and air to the supply tank.

5 7. A two-stage oil burner pump having, in combination, a first stage pumping means, a second stage pumping means, a reservoir to which the inlet to the second stage pumping means is connected below the level at which the oil stands 10 during normal operating conditions, a supply tank connection leading to said reservoir above the normal operating level of the oil therein, an inlet passage connected to the first stage pumping means and opening to said reservoir, the opening of said passage being bisected by the oil 15 at normal level in the reservoir to enable the first stage pumping means to withdraw excess oil and any air above said level, a discharge connection from the first stage pumping means for returning excess oil and air to the supply tank, and a discharge connection from the second stage pumping means for returning excess oil pumped thereby to the reservoir.

20 8. A two-stage oil burner pump having, in combination, a casing, a first stage pumping means in the casing, a second stage pumping means in the casing, a reservoir in the casing to which the inlet to the second stage pumping means is connected below the level at which the oil stands 25 during normal operating conditions, a supply tank connection leading to said reservoir above the normal operating level of the oil therein, an inlet connection for the first stage pumping means communicating with said reservoir at the normal oil level to enable the first stage pumping means to withdraw excess oil and any air above said level, a pressure operated burner 30 shutoff valve connected to the outlet of the second stage pumping means, means controlled by the valve for bypassing excess fluid pumped by the second stage pumping means, and a passage 35 connecting the bypass means to the reservoir to return thereto such excess fluid.

40 WILLIAM RAY KIEFER.
